UNITED STATES PATENT OFFICE.

GIUSEPPE SANTILLI, OF ASTORIA, NEW YORK.

DUAL TYPEWRITING MECHANISM AND DESK STRUCTURE.

Application filed May 11, 1928. Serial No. 276,917.

This invention relates to certain new and useful improvements in dual typewriting machines and desk structures and has for one of its objects to provide for the simultaneous operation of a pair of independent typewriting machines from a single key board operatively associated with the two separate machines whereby two letters or other papers may be written in the "original" at the same time.

A further object of the invention is to provide a dual typewriting machine and desk structure wherein the desk structure comprises sliding shelves or top sections supporting typewriters and an intermediate area for access to an operating key board for the two separate typewriters, the desk structure permitting either automatic operation of the two separate typewriting machines or individual direct manual operation of each machine.

A still further object of the invention is to provide novel devices for the simultaneous operation of the separate typewriting machine by the use of a single key board with a novel system of controlled levers, links and catch devices for sliding top sections of the desk structure.

With the above and other objects in view that will become apparent as the nature of the invention is better understood, the same consists in the novel form, combination and arrangement of parts hereinafter more fully described, shown in the accompanying drawings and claimed.

In the drawings:

Figure 1 is a top plan view of the typewriter desk structure showing the sliding top sections and the control levers therefor;

Figure 2 is a front elevational view of the desk structure;

Figure 3 is a top plan view with the sliding top sections moved rearwardly to permit the single typewriter key board and the double operating devices for separate typewriting machines to be moved into operative positions;

Figure 4 is a fragmentary perspective view showing a part of the dual operating mechanism for the separate typewriters;

Figure 5 is a vertical cross-sectional view taken on line 5—5 of Figure 1, showing the operating mechanism for the typewriter disposed beneath the top of the desk construction;

Figure 6 is a fragmentary side elevational view of one of the auxiliary operating levers for a typewriter key arm;

Figure 7 is a vertical cross-sectional view taken on line 7—7 of Figure 1 showing the typewriter operating mechanism raised to its operative position with the operating lever thereof engaged with the keys of a typewriter;

Figure 8 is a fragmentary side elevational view, partly in section showing the devices for holding the typewriter mechanism in its elevated position with the typewriter key engaging levers slightly disposed above the typewriter keys; and

Figure 9 is a view, similar to Figure 8 in which the typewriter key operating levers are slightly lowered into engagement with the typewriter keys.

The dual typewriter mechanism is associated with a typewriter desk structure in which the desk comprises supporting legs 1 and top 2, the top 2 comprising a rigid section 3 extending longitudinally of the top adjacent the rear edge while the forward side of the desk top is provided with a central opening 4 and lateral openings 5 separated by rails 6. The operating mechanism for the two typewriters is normally disposed beneath the table top 2 and comprises a single key board that is movable upwardly through the central opening 4, while the operating devices for the two separate typewriting machines is movable upwardly through the lateral openings 5.

The table top openings are closed by the sliding top sections 7 and 8 respectively overlying the central opening 4 and lateral openings 5, the lower faces of the sliding table top sections being provided with depending ribs 9 engageable with the table top for limiting sliding movement thereof. A typewriting machine is to be carried by each end top section 8 as illustrated by dotted lines in Figure 7, while a rack or cabinet 10 is carried by the top section 7 as shown in Figures 1 and 2.

Devices are associated with the lateral sliding table top sections 8 for holding them in adjusted positions and comprise a plurality of links and levers primarily operated upon movement of the middle top sliding section 7. As shown in Figures 1 and 3, each rear corner of the top section 7 carries a perpendicular stud 11 upon which the lever 12 is pivotally supported, the rear short

ends of the lever 12 being connected together by the spring 13 and limited in a movement toward each other by the short ends of said levers moving into engagement with the stop pins 14 on the top section 7. The opposite longer end of each lever 12 carries a depending pin 15 for purposes presently to appear. As shown more clearly in Figure 3, the rear inner side edge of each lateral top section 8 carries a longitudinally extending strip 16 provided with free spaced edge notches 17, 18 and 19. A lever 20 is pivotally mounted as at 21 upon each rail 6 and has pins 22 and 23 depending from opposite ends thereof. A relatively long lever 24 is pivotally mounted as at 25 upon the end of the table top 2 and has a link connection 26 with the lever 20.

When the middle top section 7 is at its limit of forward movement, the levers 12 are engaged with the levers 20 at point thereof forwardly of the pivotal mountings 21 so that pins 23 carried by the lever 20 are moved in directions toward the notched strips 16. When the lateral table top sections 8 are in the normally closed position, the pins 23 are engaged in the notches 19 of the strips 16 and said top sections are held against movement. When it is desired to manually operate each typewriter to the exclusion of the dual operating mechanism, the lever 24 is operated for shifting the lever 20 to disengage the pin 23 from the notch 19 and at which time the table top may be slid forwardly until the intermediate notch 18 registers with the pin 23 and is permitted to enter the notch when pressure on the lever 24 is relieved. The side levers 20 are also simultaneously operated upon the sliding movement of the middle top section 7 as shown in Figure 3, at which time, the top sections 8 are moved rearwardly to expose the table top openings 5.

The dual typewriter mechanism comprises devices movably supported beneath the desk top and include a frame having a bottom wall 27, end walls 28 and a rear wall 29; the rear wall 29 being hinged as at 30 to the rear side rail 31 of the desk structure. Descending movement of the frame structure is limited by the rear wall 29 thereof engaging the rear side rail 31 as will be understood from an inspection of Figures 5 and 7. A longitudinally extending rod 32 is fixed at its ends in the end walls 28 of the frame adjacent the rear wall 29 while another rod 33 is fixed at its ends in the frame as illustrated. A complement of typewriter key levers 34 are pivotally mounted upon the rod 32 beneath the central opening 4 of the desk top, and being tensioned in upward directions by devices presently to be described, upward movement of the key levers 34 is limited by contact with the rod 33. A plurality of operating levers of the key levers of a typewriting machine are pivotally

supported on the rod 32 adjacent each end thereof, each plurality or set of operating levers being disposed beneath the desk top opening 5, and each operating lever 35 having an upstanding hooked arm 36 with a cushion pad 37 upon the end thereof for engaging the key 38 of the typewriting machine 39. The operating levers 35 being arranged in groups adjacent each end of the rod 32, corresponding characters in the two groups are connected by a longitudinally extending strip 40 having pin connections 41 with the undersides of the operating levers 35. The strip 40 connecting corresponding levers 35 in the spaced groups also has an upstanding pin connection 42 with the corresponding operating lever 34 of the intermediately positioned complement or chest of key operating levers. The operating levers 35 are disposed below the rod 33 and said rod is provided with a plurality of perpendicular angle arms 43 having a spring connection 44 with each operating lever 35, the several springs 44 holding the levers 34 and 35 at their limits of upward movement. The typewriter key operating levers 35 and the complement of typewriter key levers 34 are adapted to be moved upwardly through the desk top openings alined therewith and the devices for raising the frame 27 and operating levers carried thereby are shown more clearly in Figures 5 to 9.

An arm 45 is fixed to the underside of the frame 27 adjacent each end thereof and extends downwardly at an angle therefrom toward the forward side of the desk structure. A longitudinally extending rod 46 is journaled in the arms 45 and has fixed to each end thereof, a latch arm 47. Each latch arm is notched upon opposite edges at different elevations as at 48 and 49 for selective engagement with pins 48^a and 49^a carried by the end drop 50 of the desk structure. The shaft 46 is rotatably tensioned in a direction to cause the notches 48 to be engaged with the pins 48^a when the arms 47 are raised and the tensioning devices include a pair of arms 51 fixed to the rod 46 adjacent each handle 45 with the free ends thereof connected by the rod 52. The arms 51 are located outwardly of the handle 45 and the springs 53 connecting the handles to the arms 51 cause rod 52 to be moved into engagement with the handle for limiting rotary movement of the rod 46.

When it is desired to use the two typewriting machines, the central top section 7 is moved rearwardly and the levers 12 carried thereby shift the levers 20 to disengage the pins 23 from the notches 19. When the levers 20 are disengaged from the sliding top sections 8, the latter are then slid rearwardly to the positions shown in Figure 3 and the pins 15 depending from the levers 12 hold the levers 20 in the position illustrated. The frame structure beneath the

desk top is then elevated by the handles 45 upon the hinge mounting 30, the complement or bank of typewriting keys 34 being moved upwardly into the opening 4 of the desk top, 5 while the hook arms 36 of the operating levers 35 are moved upwardly into the desk top openings 5. The arms 47 have the notches 49 thereof engaged with the pins 49^a for holding the operating mechanism raised. 10 When the top sections 8 are in the positions shown in Figure 3, the pins 22 of the levers 20 are engaged in the intermediate slots 18 of the strips 16 to hold the top sections against movement. With the operating 15 levers 35 properly positioned with the hooked ends 36 thereof disposed above the desk top, the latter with the typewriter 39 supported thereon as shown in Figure 7, is then ready to be moved forwardly to display 20 the typewriter keys 38 beneath the cushioned ends 37 of the hooked arms 36. The side lever 24 is then operated to disengage the pin 22 of the lever 20 from engagement with the strip 16 to permit forward 25 sliding movement of the top section 8. As the lever 20 is tensioned by the lever 12, the pin 22 rides over the adjacent edge of the strip 16 until the notch 17 is positioned to receive the pin 22 and at which time sliding 30 movement of the top section 8 is arrested. In this position, the ends of the operating levers 35 are disposed directly above an associated typewriter key 38 and slightly spaced from the same. At this time, a slight 35 upward movement of the operating devices will cause the arms 27 to be disengaged from the pins 49^a while the springs 53 will move the arms 47 to cause the notches 48 to receive the pins 48^a and be supported thereon. 40 When so disposed, the operating mechanism is slightly lowered and the cushioned ends 37 of the operating levers 35 are directly engaged with the associated keys 38 of the typewriting machine. The middle bank of 45 keys 34 is then operated and by the rod connections 40 with associated operating levers 35, corresponding characters of the two typewriting machines are simultaneously operated. When it is desired to manually operate 50 each typewriting machine separately, and to the exclusion of the dual operating mechanism, the table top sections 8 are moved rearwardly when released by the guide levers 24 and after the operating 55 levers 35 have been slightly elevated off of the typewriter keys 38, at which time, the operating mechanism is lowered beneath the desk top. The top section 8 may then be moved forwardly until the pin 23 is engaged 60 in the intermediate notch 18 of the strip 16 and at which time, the forward end of the top section 8 will project slightly beyond the desk top for the convenient location of the typewriting machine. 65 From the above detailed description, it is

believed that the construction and operation will at once be apparent, and while there is herein shown and described the preferred embodiment of the present invention, it is nevertheless to be understood that minor changes may be made therein without departing from the spirit and scope of the invention as claimed.

What I claim as new is:—

1. In a desk construction for dual typewriting mechanism, a desk top having sliding top sections covering central and lateral openings spaced by rails, notched strips carried by the top sections, one strip overlying each of the lateral openings, a series of inter-engaged levers carried by the desk top and central top sections and engageable with the strips for holding the lateral top sections in adjusted positions, and dual typewriter operating mechanism disposed beneath the desk top and movable upwardly through the openings. 75

2. In a desk construction for dual typewriting mechanism, a desk top having sliding top sections covering central and lateral openings spaced by rails, notched strips carried by the top sections, one strip overlying each of the lateral openings, a series of inter-engaged levers carried by the desk top and central top sections and engageable with the strips for holding the lateral top sections in adjusted positions, dual typewriter operating mechanism disposed beneath the desk top and movable upwardly through the openings, and a spring for the levers on the central top section for normally moving a lever on the desk top into engagement with a strip. 90

3. In a desk construction for dual typewriting mechanism, a desk top having sliding top sections covering central and lateral openings spaced by rails, notched strips carried by the top sections, one strip overlying each of the lateral openings, a series of inter-engaged levers carried by the desk top and central top sections and engageable with the strips for holding the lateral top sections in adjusted positions, dual typewriter operating mechanism disposed beneath the desk top and movable upwardly through the openings, a spring for the levers on the central top section for normally moving a lever on the desk top into engagement with a strip, and a manually operable lever on each end of the desk top for releasing the levers from engagement with the strips. 105

4. In a desk construction for dual typewriting mechanism, a desk top having sliding top sections covering central and lateral openings spaced by rails, notched strips carried by the top sections, one strip overlying each of the lateral openings, a series of inter-engaged levers carried by the desk top and central top sections and engageable with the strips for holding the lateral top sections 110

in adjusted positions, dual typewriter operating mechanism disposed beneath the desk top and movable upwardly through the openings, the typewriting mechanism comprising a frame hinged beneath the desk top, a central bank of typewriter keys carried by the frame, lateral sets of typewriter key operating levers on the frame, connections between corresponding typewriter keys and operating levers, and means for holding the typewriter operating mechanism in a raised position with the operating levers adapted to be engaged with the keys of typewriting machines mounted on the lateral desk top sections.

5. In a desk construction for dual typewriting mechanism, a desk top having sliding top sections covering central and lateral openings spaced by rails, notched strips carried by the top sections, one strip overlying each of the lateral openings, a series of inter-engaged levers carried by the desk top and central top sections and engageable with the strips for holding the lateral top sections in 10 adjusted positions, dual typewriter operating mechanism disposed beneath the desk top and movable upwardly through the openings, a spring for the levers on the central top section for normally moving a lever 15 on the desk top into engagement with a strip, the typewriter operating mechanism comprising a frame hinged beneath the desk top, a central bank of typewriter keys carried by the frame, lateral sets of typewriter key operating levers on the frame, connections 20 between corresponding typewriter keys and operating levers, and means for holding the typewriter operating mechanism in a raised position with the operating levers 25 adapted to be engaged with the keys of typewriting machines mounted on the lateral desk top sections.

6. In a desk construction for dual typewriting mechanism, a desk top having sliding top sections covering central and lateral openings spaced by rails, notched strips carried by the top sections, one strip overlying each of the lateral openings, a series of inter-engaged levers carried by the desk top 30 and central top sections and engageable with the strips for holding the lateral top sections in adjusted positions, dual typewriter operating mechanism disposed beneath the desk top and movable upwardly through the 35 openings, a spring for the levers on the central top section for normally moving a lever on the desk top into engagement with a strip, a manually operable lever on each end of the desk top for releasing the levers from 40 engagement with the strips, the typewriter operating mechanism comprising a frame hinged beneath the desk top, a central bank of typewriter keys carried by the frame, lateral sets of typewriter key operating 45 levers on the frame, connections between cor-

responding typewriter keys and operating levers, and means for holding the typewriter operating mechanism in a raised position with the operating levers adapted to be engaged with the keys of typewriting machines mounted on the lateral desk top sections.

7. In a desk construction for dual typewriting mechanism, a desk top having sliding top sections covering central and lateral openings spaced by rails, notched strips carried by the top sections, one strip overlying each of the lateral openings, a series of inter-engaged levers carried by the desk top and central top sections and engageable with the strips for holding the lateral top sections in adjusted positions, dual typewriter operating mechanism disposed beneath the desk top and movable upwardly through the openings, the typewriter operating mechanism comprising a frame hinged beneath the desk top, a central bank of typewriter keys carried by the frame, lateral sets of typewriter key operating levers on the frame, connections between corresponding typewriter keys and operating levers, and means for holding the typewriter operating mechanism in a raised position with the operating levers adapted to be engaged with the keys of typewriting machines mounted on the lateral desk top sections, the last named means having two rest positions permitting movement of the desk tops and machines beneath the ends of the operating levers and subsequently supporting the levers in a lowered position engaged with the typewriter keys.

8. In a desk construction for dual typewriting mechanism, a desk top having sliding top sections covering central and lateral openings spaced by rails, notched strips carried by the top sections, one strip overlying each of the lateral openings, a series of inter-engaged levers carried by the desk top and central top sections and engageable with the strips for holding the lateral top sections in adjusted positions, dual typewriter operating mechanism disposed beneath the desk top and movable upwardly through the openings, a spring for the levers on the central top section for normally moving a lever on the desk top into engagement with a strip, the typewriter operating mechanism comprising a frame hinged beneath the desk top, a central bank of typewriter keys carried by the frame, lateral sets of typewriter key operating levers on the frame, connections between corresponding typewriter keys and operating levers, and means for holding the typewriter operating mechanism in a raised position with the operating levers adapted to be engaged with the keys of typewriting machines mounted on the lateral desk top sections, the last named means having two rest positions permitting movement of the desk tops and machines beneath the ends of the operating levers and subsequently supporting the levers in a lowered position engaged with the typewriter keys.

ends of the operating levers and subsequently supporting the levers in a lowered position engaged with the typewriter keys.

9. In a desk construction for dual type-writing mechanism, a desk top having sliding top sections covering central and lateral openings spaced by rails, notched strips carried by the top sections, one strip overlying each of the lateral openings, a series of inter-engaged levers carried by the desk top and central top sections and engageable with the strips for holding the lateral top sections in adjusted positions, dual typewriter operating mechanism disposed beneath the desk top and movable upwardly through the openings, a spring for the levers on the central top section for normally moving a lever on the desk top into engagement with a strip, a manually operable lever on each end of the desk top for releasing the levers from en-

gagement with the strips, the typewriter operating mechanism comprising a frame hinged beneath the desk top, a central bank of typewriter keys carried by the frame, lateral sets of typewriter key operating levers on the frame, connections between corresponding typewriter keys and operating levers, and means for holding the typewriter operating mechanism in a raised position with the operating levers adapted to be engaged with the keys of typewriting machines mounted on the lateral desk top sections, the last named means having two rest positions permitting movement of the desk tops and machines beneath the ends of the operating levers and subsequently supporting the levers in a lowered position engaged with the typewriter keys.

In testimony whereof I affix my signature.
GIUSEPPE SANTILLI.
